No 1,044.

W. P. Mandrotto's Design on Cork Stove.
Patented Aug. 31, 1858.

Des. 1044

Wm P. Abendroth, of Port Chester, N. Y.
Letters Patent No. 1044, dated Aug. 31, 1858.

The schedule referred to in these Letters Patent and making part of the same.

To all whom it may concern:

Be it Known that I, W. P. Abendroth, of Port Chester, in the County of Westchester, and State of New York, have invented or produced a new and ornamental design for a Cook Stove, and I do hereby declare that the fol-

is a full, clear and exact description of the same, reference being had to the annexed drawings making a part of this specification, in which,

Fig. 1. is a front view of a Cook Stove of my design.

Fig. 2. is a side view of do.

Fig. 3. is a detached view of a door of the opposite side of do.

Fig. 4. is a back view of do.

Fig. 5. is a detached view of a foot of do.

This design is one of rather a national character and is intended to excite some degree of interest as well as to present an ornamental appearance. The front side of the stove has four doors, the two upper ones A. A. see fig. 1, through which the fire is supplied with fuel has scrolls a, formed on them with a flower b, at the center. The scrolls being bounded with plain beads c, which form the boundary of the doors. The two lower doors B. B. have their panels ornamented with scrolls d, d at the center of each of which there is the head e, of an Indian surmounted with feathers f. The doors B. have plain beads g, at their edges and near each edge of the front plate there are two set scroll figures h, i.

The side plates one of which is shown fully in fig. 2, are embellished at one side with a scroll corner piece j, and a set scroll figure k, similar to figures i, on the front plate. At the opposite side there is a scroll l, formed on a raised panel or door C, and a set figure m, beneath it. The above named parts are common to both sides of the stove, but the design on the panels of the oven doors D, are different, but both illustrating thefeat of General Putman. On one panel n, fig. 6, the General on horse back is represented as being pursued by the British dragoons, and on the panel o, of the opposite side see fig. 2, the General is descending on horse back the stone steps on the hill side at a rapid speed.

The back plate of the stove is provided with three set scroll figures p, q, q, the center figure p, has a smaller figure or beaded border r, within it.

The scrolls q, q, are precisely the same with the exception of being reversed in position. The foot s, shown in fig. 5, is formed of a series of scrolls.

The several scrolls although differing somewhat in form still harmonize with each other and in connection with the other named parts form a classic and ornamental design for a cook stove.

Des. 1044

What I claim as new and desire to secure by Letters Patent, is.
The general configuration of the parts shown on the front, sides
and back of the Stove to form a new and Ornamental design for a Cork Stove.

Witnesses,

O. D. Munn.

J. W. Combs.

W. P. Abendroth.
